UNITED STATES PATENT OFFICE.

FRANK H. POEPPELMEIER, OF DAYTON, OHIO, ASSIGNOR TO THE TYPOGRAPHIC MACHINES COMPANY, OF DAYTON, OHIO, A CORPORATION OF OHIO.

TYPE-COMPOSING BOARD.

Application filed December 13, 1926. Serial No. 154,397.

This invention relates to new and useful improvements in type composing boards.

It is the principal object of my invention to provide a simple, compact and efficient type 5 composing board to receive type and direct them downwardly to a composing ejector in a manner least likely to obstruct or clog the tubes and channels through which they descend.

10 The invention contemplates a core board support for a plurality of twisted tubes by which the type, in their passage therethrough, are turned 90° for presentation in an edgewise manner to oblique side channels by which 15 the type are conducted to vertical channels for delivery to the composing ejector.

It is another object of the invention to provide for the side channels, cover plates having transparent portions through which the 20 type are visible.

It is still another object of the invention to provide hinged means for these cover plates whereby they may be drawn from the side channels for cleansing purposes and to permit the easy removal of a broken or imperfect 25 type which obstructs the passage of the other type through them.

Other important and incidental objects will 30 be brought out in the following specification and particularly set forth in the subjoined claims.

In the accompanying drawings illustrating 35 my invention, Figure 1 is a perspective view of a composing machine equipped with my improved type composing board. Figure 2 is a front elevational view of the type composing board, partly broken away to reveal the twisted type tubes. Figure 3 is a top plan view of the same. Figure 4 is a cross 40 sectional view taken through the type receiving channels at the bottom of the board on the line 4—4 of Figure 2. Figure 5 is a side view of the type composing board, partly broken away to reveal the ends of the 45 twisted type tubes. Figure 6 is a view of the lower end of the type composing board. Figure 7 is a sectional view taken through one edge of the type composing board on the line 7—7 of Figure 2. And Figure 8 is a 50 perspective view of one of the twisted type receiving tubes.

Referring to the accompanying drawings for a detailed description of my invention, Figure 1 illustrates a type composing machine 55 having a triangular core board 1 preferably

constructed of brass. Secured to each side of this board is a plurality of vertical type tubes 2 which receive type from an ejector 2*. At their lower ends these tubes or chutes 2 are spirally turned or twisted a sufficient amount 60 to change the position of the type passing through them 90°, so that they will enter edgewise or the narrow way, inclined channels 3, 3 provided at each side edge of the board 1 by means to be hereinafter described. 65

The core board 1 is secured at its upper end to a head member 4 along which the upper ends of the type tubes 2 project. Formed on each lower side portion of the head member 4 is an ear 5 which is straddled by the 70 upper forked end 6 of a channel cover plate 7. By a pin 8 passing through each ear 5 and the formed end of its respective cover plate 7, the latter is hingedly secured to said ear for a swinging movement with respect to 75 the adjacent edge of the core board. Each cover plate 7 is grooved at its middle portion to fit the edge of the core board 1, to form the two oblique side channels 3, 3 which receive the type edgewise from the tubes 2. 80

Secured to the sides of each channel cover plate 7 by screws 9 are members 10, 10 constructed of non-breakable transparent material. These transparent members 10, 10 by exposing to view the type within the channels 85 3, 3, make it possible to readily detect the clogging up of them by broken or imperfect type. And when this occurs, the cover plate 7 over that particular type may be swung away from the channel to permit the removal 90 of that type from it. The channels are thus easily kept open for the free passage of type through them at all times.

The type tubes 2 are covered on each side by a triangular plate 11. The type which 95 enters and is turned by these tubes, descends edgewise into channels 3, 3 just described for delivery by them in their edgewise positions to a single vertical channel 12 formed between blocks 13, 13 secured to each side of 100 the lower projecting part of the core board 1 by screws 14. By these two channels 12, 12 the type is delivered to a composing ejector 15.

Provided in the lower ends of the channel 105 cover plates 7, 7 are longitudinal slots 16 which receive slides 17 having tapered inner ends that engage pins 18 on the lower end of the core board. (See Figures 2 and 4.) Handles 19 are formed on the upper ends 110

of these slides so that they may be easily shifted to engage their inner tapered ends with the pins 18 when it is desired to lock the channel cover plates 7 to the core board and to withdraw said slides from engagement with said pins when it is desired to swing the cover plates away from the channels 3 to clear them of obstructions.

Having described my invention, I claim:

- 10 1. In a device of the type described, the combination with a type composing board, of a plurality of type receiving tubes vertically disposed thereon, oblique side channels communicating with the lower ends of the type receiving tubes, and to which the type is delivered edgewise by said tubes, and a common discharge means into which the type is delivered to the side channels.
- 15 2. In a device of the type described, the combination with a type composing board, of a plurality of type receiving tubes vertically disposed thereon and twisted at their lower ends, oblique side channels communicating with the twisted lower ends of said type receiving tubes, and a common discharge means into which the type is delivered by the side channels.
- 20 3. In a device of the type described, the combination with a type composing board, of a plurality of type receiving tubes vertically disposed thereon, oblique side channels communicating with the lower ends of the type receiving tubes, a common discharge means into which the type is delivered by the side channels, and hinged cover plates for the side channels.

4. In a device of the type described, a triangular core board, type receiving tubes applied to said board and terminating at their lower ends a short distance from the side edges of said board, cover members hingedly secured at the upper corner portions of said board and formed with grooves adapted to fit the side edges of said core board to form between the cover members and the type tubes, oblique type channels, and transparent plates secured to the cover members over said channels.

5. In a device of the type described, the combination with a triangular type composing board having a bottom projecting part, blocks secured to said projecting part of the core board to provide between them a vertical type receiving channel, and means forming at the side edges of said board, channels which conduct the type to said vertical channel.

6. In a device of the type described, the combination with a triangular type composing board, a vertical type discharge channel at the lower end of said board, channels at the side edges of said board for conducting type to the discharge channel, cover plates hingedly secured at their upper ends for the side channels, pins fixedly attached to said board at its lower end, and slides carried by the cover plates for engagement with the pins to lock said plates over the side channels.

In testimony whereof I have hereunto set my hand this 8th day of December, 1926.

FRANK H. POEPPELMEIER.
